UNITED STATES PATENT OFFICE.

JAMES C. MEEM, OF BROOKLYN, NEW YORK, ASSIGNOR OF ONE-THIRD TO FREDERICK L. CRANFORD AND ONE-THIRD TO WALTER V. CRANFORD, OF BROOKLYN, NEW YORK.

METHOD OF CONSTRUCTION.

No. 896,064.

Specification of Letters Patent.

Patented Aug. 11, 1908.

Original application filed September 6, 1907, Serial No. 391,577. Divided and this application filed April 1, 1908.
Serial No. 424,569.

To all whom it may concern:

Be it known that I, JAMES C. MEEM, a citizen of the United States, residing at Brooklyn, in the county of Kings and State of New York, have invented certain new and useful Improvements in Methods of Construction, of which the following is a full, clear, and exact specification.

This invention relates to a method of partially submerged construction, and more particularly has reference to a method whereby structures such as foundations, tunnels, or other structures, or portions of structures, partly above and partly below the water, may be safely constructed continuously and rapidly, at a low cost and without injury to adjacent property.

In carrying out the method of the invention, a preliminary excavation is made down to the water level and preferably is somewhat larger than the tunnel or foundation to be constructed. Within this excavation, sheeting or piling to form a fixed caisson, is set up and driven to a level below the water level, leaving a stationary portion thereof extending above the water level. This stationary portion is air proofed and weighted so as to form a caisson where necessary, and provided with the usual air locks and other apparatus. Having erected this caisson, it is now possible to excavate from the interior, under air pressure where necessary, to hold back the water, in the usual manner. In going to a greater depth than the sheeting first driven, additional sheeting and bracing are driven on the forward end in such manner as not to restrict the clear space, so that the interior of the caisson has a certain minimum area and is protected from caving in. This caisson forms one section of the structure to be erected, and from the level as finally determined, whether wholly or partly below the water level, additional sections will be excavated from within the first section while the latter is being lined, or other structure built therein, each succeeding section having a roof, and piling driven as described, and being separated by temporary bulkheads from the sections in a more advanced stage. By this method the structure can be erected in sections, each at a different stage of completion, continuously, and without the necessity of opening the whole excavation at once, or opening separate blocks.

The invention will be more fully understood in connection with the accompanying drawings, in which

Figure 1 is a sectional view showing one section of a tunnel or foundation in course of construction, wherein the excavation is made down to the water level and the stationary caisson and air locks are in place ready for the interior excavation, and Fig. 2 shows a plan view of the several sections of a subway or tunnel in course of construction in different stages of completion.

Referring to Figs. 1 and 2, A represents the ground in which the tunnel or foundation is to be commenced or built, and B represents the water level therein either the normal water level or a temporarily lowered water level produced by pumping.

C represents an excavation made down to the water level B, and shored up or braced by sheet piling D and cross braces E. Within this excavation C are driven sheet piles F closely together, around the space to be excavated under the water level B, and these piles F are braced by horizontal braces G, in the usual manner. The top of the piles F is leveled off and provided with a waling H, and secured to the piles and the waling is a roof I, provided with passages J having the usual air locks and air pipes therein. The roof I is made to be stationary and for this purpose may be loaded with timbers or concrete K to resist the upward reaction of the air pressure and may be braced within the piles F by braces L. The piles F having been driven, the roof put on, and the space above the water level B air proofed in the usual manner, the interior of the caisson can now be excavated, under air if necessary, or the water kept back by pumping. As the excavation goes onward, the sides of the caisson will be braced, and when the excavation has reached the bottoms of the piles, in case it is desired to go further, additional piles or sides M will be added as the excavation proceeds. These additional sides or extensions M are made of somewhat shorter sections of sheet piling driven downwardly and outwardly at an incline, and having the joints closed, as by concrete N, and suitably braced, so that the whole forms a rigid structure. In doing this, the water and the ground, such as quick sand or mud, may be held back by the air pressure. When the excavation has

proceeded in this manner as far downward as is desired, it will be filled up, in the case of a foundation, or lined, as in the case of a tunnel or subway,

5 Fig. 2 shows a subway in process of construction in which a new section P is being built, and the sections Q, R and S in different stages of completion. The section P, in course of excavation, similar to Fig. 1, has 10 temporary bulkheads at the ends closing it off from the excavated and unexcavated portion of the work. The section R has been entirely completed inside the piling, and temporarily closed at the front end by a 15 block of concrete or timbers T behind the piling bulkhead; the section Q has been excavated (under air pressure, if necessary); and the section S is being started by driving the first sheeting. In the section Q, the masonry 20 is started as soon as the excavation is sufficiently advanced, and the bulkhead between it and section P partially or wholly removed so that section P can be excavated under the same air pressure used in section 25 Q, thus avoiding the necessity of building air locks for each section. Section P having been excavated, the bulkhead between it and section S will be opened, and the latter excavated.

30 It will of course be understood that each section is roofed and weighted, whether provided with an air lock or not, and this process of working from one section into the adjoining one, while erecting the masonry in the 35 excavated ones, can be continued until the total air leakage in the sections under air becomes excessive, whereupon a bulkhead will be erected and one of the advanced sections provided with an air lock, and excavated 40 through this air lock. In this manner, a tunnel can be rapidly and economically constructed, without the necessity of driving built-up caissons. In driving built-up caissons side by side, it is necessary to cut 45 through from one to the other, and this cutting through is dangerous, because a large space is left entirely unprotected from cave-in while the masonry in the two sections is being connected. At this point, the ground 50 may shift and cause damage to surrounding property as well as to completed portions of the tunnel itself, but such contingency is entirely prevented by the method of this invention. According to this method, only 55 the transverse bulkheads separating the sections have to be removed, and a number of sections can be in course of construction at once.

It will be seen that by this method, it is 60 unnecessary to move the whole caisson as the work progresses, which is an expensive and objectionable process. In forcing built-up caissons as the excavation proceeds, and especially in soils containing boulders, the 65 progress of the whole caisson may be stopped

by a boulder, whereas by this method of driving piles, only those piles which strike the boulder will be stopped and the others can be driven as far as is desirable. After the interior has been excavated to the rock, 70 it can be broken up and removed, or a new set of piles can be driven onward from around the rock. In this manner, excavations can be made under water by means of caisson sections which are built in the direction of 75 the excavation as it proceeds, the water and soil being held back by air pressure where necessary, and one excavated through an adjoining one in a more advanced stage of completion.

80 It will also be understood that I do not restrict myself to any particular location of the air locks, which are shown herein in the fixed roof, as these may be located in the side walls, or elsewhere if desired, without affecting or departing from the scope of the invention.

90 While I have illustrated and described herein a novel method of construction of a single section, such method is not claimed herein, but in an application filed by me September 6, 1907, Serial No. 391577, Patent 884,990, issued April 14, 1908, of which application this present application is a division.

95 Having thus described my invention, I declare that what I claim as new and desire to secure by Letters Patent, is,—

1. A method of building a submerged structure consisting in dividing the same into sections by piling and bulkheads, roofing the 100 sections with a fixed roof, excavating one section under air pressure, and excavating the second roofed section through said first excavated section.

2. A method of building a submerged 105 structure consisting in dividing the same into sections by piling and bulkheads, roofing the sections with a fixed roof, excavating one section under air pressure, erecting the permanent structure therein, and excavating 110 the second roofed section through said first excavated section while the permanent structure therein is in course of erection.

3. A method of building a submerged 115 structure consisting in erecting a plurality of adjoining caissons, each having a roof fixed to withstand air pressure, one of said roofed sections having an air lock, excavating 120 said section first, and then connecting said section and adjoining sections successively, and excavating said adjoining sections through said first section, while erecting the permanent structure therein.

In testimony whereof I affix my signature in presence of two witnesses.

JAMES C. MEEM.
